UNITED STATES PATENT OFFICE

ADOLPH SCHRÖR, OF BREMEN, GERMANY.

BOILER-SCALE-REMOVING APPARATUS.

No. 909,235.

Specification of Letters Patent. Patented Jan. 12, 1909.

Application filed September 4, 1908. Serial No. 451,766.

To all whom it may concern:

Be it known that I, ADOLPH SCHRÖR, a subject of the Emperor of Germany, and a resident of Bremen, Germany, have invented 5 certain new and useful Improvements in Boiler-Scale-Removing Apparatus, of which the following is a specification.

This invention relates to apparatus for removing boiler scale and the like of the type 10 wherein one or more cleaning rolls are mounted in a frame and the object of this invention is to provide an apparatus which can be easily handled.

According to this invention the handle of 15 the frame is formed hollow and has a shaft mounted therein, this shaft being rotated by any convenient means and connected to the cleaning rolls by toothed wheels. The toothed wheels are of such size that the rolls 20 rotate at a much greater speed than has hitherto been the case and cleaning can thus be done much more quickly and efficiently.

In the accompanying drawings, Figure 1 shows an apparatus according to this invention 25 in front elevation partly in section. Fig. 2 is an end view of the same and Fig. 3 is a section on the line *a*—*b* of Fig. 1.

In the construction illustrated the frame A consists of a head piece, having a base plate 30 *a* and side plates *a'*, *a''*, and a hollow handle *G* within which is mounted a driving shaft *H*. Keyed on the end of this shaft within the frame is a bevel wheel *B* meshing with a bevel pinion *B'*, rigidly secured to a counter- 35 shaft *B''* journaled in the frame. This countershaft also has keyed to it a toothed wheel *C* which meshes with a pinion *F* on the spindle *D* of the cleaning roll *E*. When the driving shaft in the handle is rotated the bevel 40 pinion *B* mounted thereon meshing with the small bevel pinion *B'* rotates the toothed wheel *C* and thus drives the spindle *D* and the cleaning roll with a great speed.

The roll may be provided with teeth, wire 45 bristles or the like according to the nature of the surface to be cleaned and the length, shape or number of rolls may be varied to suit requirements. Thus for instance when boiler scale is to be removed from rivet heads 50 the diameter of the roll may be from 28 to 40 mm. As shown in the drawings the toothed periphery of the cleaning roll projects beyond the outer ends of the side plates of the supporting frame. The cleaning rolls may be 55 changed when desired and this is preferably effected by mounting the brasses *d* wherein

the spindles of the cleaning rolls and countershaft are journaled in dovetailed slots in the frame, suitable means being provided for holding the brasses in place. 60

The power for the driving shaft is conveniently derived from some flexible shafting for instance that of an electromotor so that the device can be moved about as desired.

It will be seen that all of the gearing is ar- 65 ranged within the head piece and between the inwardly extending flanges of the members *a*, *a'*, *a''* thereof. As shown the pinion *B* on the inner end of the shaft *H* has a bearing against the base plate *a* of the head piece of 70 the frame, in which bearing antifriction balls may be arranged.

What I claim as my invention and desire to secure by Letters Patent is:—

1. The herein described apparatus for removing boiler scale comprising a frame including a forked head and a tubular handle attached to said head, two parallel shafts journaled in the side members of the head of the frame and geared together, a cleaning 75 roll mounted on one of said shafts, a bevel gear connected to the other shaft, a driving shaft extending through the tubular handle and into the head piece of the frame, and a second bevel gear secured to the end of said 80 shaft within the head piece of the frame and meshing with the aforesaid bevel gear. 85

2. The herein described apparatus for removing boiler scale comprising a frame including a forked head piece, consisting of a 90 base plate and parallel side plates, and a tubular handle attached to the base plate of said head plate, a cleaning roll mounted on a shaft journaled in bearings in the side plates of the head, the periphery of said roll 95 projecting beyond the outer ends of said plates, a pinion on the shaft of the roll, a driving shaft extending through the tubular handle of the frame and the base plate of the head piece, a gear mounted on the inner end 100 of said driving shaft, and gearing connecting the last said gear with the pinion on the roll shaft, all of said gearing being inclosed within the forked head piece of the frame. 105

In testimony whereof I have signed my name to this specification in the presence of two subscribing witnesses.

ADOLPH SCHRÖR.
